(57) **CLAIM**

The ornamental design for a dog leash, as shown and described.

DESCRIPTION

FIG. 1 is a front side view of a dog leash, in an assembled configuration, showing my new design;

FIG. 2 is a back side view of the dog leash, in the assembled configuration;

FIG. 3 is a bottom view of the dog leash, in the assembled configuration;

FIG. 4 is a top view of the dog leash, in the assembled configuration;

FIG. 5 is a right side view of the dog leash, in the assembled configuration;

FIG. 6 is a left side view of the dog leash, in the assembled configuration;

FIG. 7 is a perspective view of the dog leash, in the assembled configuration; and,

FIG. 8 is a perspective view of the dog leash of FIG. 1, shown in second configuration with two parts of the dog leash separated and a clip attached to the dog leash.

The dog leash is shown with a symbolic break in its length in FIGS. 1-2 and 5-8. The appearance of any portion of the article between the break lines forms no part of the claimed design.
